CLIP FOR A WRITING INSTRUMENT

Charles K. Lovejoy, Atlanta, Ga., assignor to Scripto, Inc., a corporation of Georgia

Filed July 12, 1960, Ser. No. 61,318

Term of patent 14 years

(Cl. D74—2)

FIG. 1 is a front elevational view of a clip for a writing instrument, showing my new design, the broken line scoring on the clip and the dot-dash line showing of parts of the writing instrument being for illustrative purposes;

FIG. 2 is a side elevational view thereof;

FIG. 3 is a top plan view; and

FIG. 4 is a front perspective view thereof.

I claim:

The ornamental design for a clip for a writing instrument, as shown and described.
